(57) **CLAIM**

The ornamental design for a vehicle front fascia, as shown and described.

DESCRIPTION

FIG. 1 is a front view of the vehicle front fascia; FIG. 2 is a left side elevation view thereof, wherein the right side elevation view is a mirror image; FIG. 3 is a top plan view thereof; and, FIG. 4 is a perspective view thereof.

The broken lines shown in the drawings illustrate portions of the vehicle front fascia that form no part of the claimed design.
